Inventor,

Frederick E. Walden;

By *A. B. L. Shantz,*
Attorney.

UNITED STATES PATENT OFFICE.

FREDERICK E. WALDEN, OF WORCESTER, MASSACHUSETTS, ASSIGNOR TO WALDEN MANUFACTURING COMPANY, OF WORCESTER, MASSACHUSETTS, A CORPORATION OF MASSACHUSETTS.

WRENCH.

No. 890,111.

Specification of Letters Patent.

Patented June 9, 1908.

Application filed April 26, 1906. Serial No. 313,822.

To all whom it may concern:

Be it known that I, FREDERICK E. WALDEN, a citizen of the United States, and a resident of the city and county of Worcester, 5 Commonwealth of Massachusetts, have made certain new and useful Improvements in Wrenches, of which the following is a full, clear, and exact description.

The object of this invention is the construction of a ratchet wrench capable of being sold at the lowest possible price, and to this end I form the same from two pieces of metal only, one of which composes one of the jaws, and the other the handle, pawl and the opposing member of the jaws.

Referring to the drawings forming part of this specification, Figure 1 is a side view of a wrench made in accordance with my invention. Fig. 2 is a cross section of the same on the line X—X in Fig. 1. Fig. 3 is a cross section on the line Y—Y in Fig. 1.

This wrench is designed for the purpose of fitting any of a large range of nuts and bolts, and consists of a length of wire rod bent into 25 three sections, one of which performs the function of fixed jaw, another of the handle, and the third of a spring pawl, and a movable jaw formed with longitudinally disposed ratchet teeth engaged by said pawl; the 30 fixed and movable jaws being held at each of several distances apart by such engagement.

As illustrated, the movable jaw 20 is formed with a nut or bolt-engaging surface 21, and an arm 24 having ratchet teeth 25 35 along its inner surface. Through said movable member are two holes penetrated by two parallel sections 30, 32 of the wire rod, by which said member is kept from turning while permitted free slidable motion. A portion 40 31 of said wire rod is formed as the fixed opposing member to the movable jaw 20, while the terminal section 33 is bent over nearly parallel with the handle section 30 into resilient engagement with the teeth 25.

45 By giving the pawl-section a slight lateral bend so that it resiliently presses against a surface, here illustrated as the bar 26 extending from the end of the arm 23 to the end of the arm 24, the pawl is prevented from slipping sidewise away from its engagement with the ratchet teeth.

As shown, the holes or openings for the rod-sections may be formed by bending the

flanges 22 over said sections 30, 32 after the latter have been placed therein; such arrangement permitting the movable member to be punched or forged, or made as a malleable iron casting.

In using this wrench, the pawl 33 is pressed away from the handle section 30 until its end 34 is disengaged from the teeth 25, and the movable jaw 20 then moved along the sections 30, 32 until the distance between the surfaces 21, 31 properly accommodates the nut, bolt-head or other article to be manipulated. The pawl 33 is now released, and by its resilience engages the tooth 25 nearest thereto. Now as the wrench is operated, the pressure brings the nearest tooth back against the pawl-end 34; after which there is no further retreat of the movable jaw, but the two jaws remain in fixed relative positions during the further movement of the wrench handle.

When the wrench jaws are at a distance apart greater than the object to be embraced thereby, it is not necessary to press the pawl 75 away from the handle section by hand, as the action of sliding the movable jaw toward the fixed one is not resisted by the pawl.

What I claim as my invention and for 80 which I desire Letters Patent is as follows, to wit:—

1. The combination of a movable jaw having suitable apertures therein, and a longitudinally arranged set of ratchet teeth, and 85 a length of metal rod in three sections, one of which penetrates one of said apertures and forms the fixed jaw, the intermediate section of which penetrates the other of said apertures, and the other terminal section of 90 which is bent over on said handle section into engagement with said teeth.

2. The combination of a movable jaw having two apertures therein and a longitudinally arranged set of ratchet teeth, and a 95 length of metal rod in three substantially parallel sections two of which penetrate said apertures and the other of which engages said teeth.

In testimony that I claim the foregoing 100 invention, I have hereunto set my hand this 23rd of April, 1906.

FREDERICK E. WALDEN.
